UNITED STATES PATENT OFFICE.

RALPH W. SHAFOR, ALPHEUS R. NEES, AND ROBERT J. BROWN, OF DENVER, COLORADO.

PRECIPITATION APPARATUS.

Application filed July 19, 1924. Serial No. 727,089.

Our invention relates to apparatus for precipitating precipitable substances from their solutions and its principal object is to accomplish in a continuous operation the formation of a precipitate in large sized particles by the application of heat to the material in a diluted condition.

The invention is particularly adapted to carry into practice a process of precipitating hot saccharates from cold waste waters obtained by the Steffens process of recovering sugar from molasses in the beet-sugar industry as fully described in our copending application for patent Serial No. 727,088, filed July 19, 1924, and in the following description the construction and operation of the apparatus in which the invention is embodied, will be more clearly brought out by reference to the above stated process which briefly is as follows.

The process is based upon the principle that by diluting a solution such as the cold waste water obtained in the before mentioned Steffens method of recovering sugar from molasses, with a larger volume of barren mother liquor, the consequently reduced concentration of the sucrose and lime in the solution will cause the formation of larger crystals upon their precipitation by means of heat.

The rate of sedimentation of the precipitate is proportionately increased and the separation of the precipitate from the mother liquor is in consequence expedited and facilitated.

The term "dilute" is used in this description in the sense of mixing a solution of solids with a liquid as defined in page 171, "Principles of Physical Chemistry", by Washburn, whereby the concentration of solids in the solution is reduced.

With the above objects in view, the process consists in producing in a suitably constructed container a circulatory movement of a volume of barren mother liquor substantially free from precipitable matter, although it may contain precipitated matter, and into this circulating current is introduced a comparatively small stream of pregnant cold waste water. The thorough intermixture of the two liquids is effected by a propeller which also serves to produce the circulating current, and an overflow of surplus

mother liquid carrying the precipitate in suspension compensates for a continuous feed of fresh material.

The precipitation of the sucrose and lime in the diluted material, either separately or combined, is produced in a zone separate from the mixing zone by heat preferably supplied through the medium of steam.

In the accompanying drawings, in the several views of which like parts are similarly designated,

Figure 1 represents a plan view of the apparatus embodying the features of our invention;

Figure 2, a vertical section taken on the line 2—2, Figure 1; and

Figure 3, a horizontal section along the line 3—3, Figure 1.

Referring more specifically to the drawings, 5 designates a tank preferably of cylindrical form, having in its bottom portion an inwardly sloping concrete fillet 7.

The top of the tank is closed by a reinforced cover 8 provided with a vent hole 9, and supported within the tank in coaxial relation to its circumferential wall is a funnel 12, the open ends of which are spaced so from the cover and from the bottom of the tank.

A screw propeller 13 in the lower end portion of the funnel is mounted upon a vertical shaft 14 supported for rotation in a step bearing 15 upon the bottom of the tank.

The shaft extends through a thrust bearing 16 which is mounted upon channel bars 17 supported on the cover 8, and it is by means of bevel gears 19 and 20 connected with a line shaft 18 which carries a pulley 21 for its connection with a conveniently located motor.

The annular space 22 in the tank exteriorly of the funnel constitutes the precipitation zone of the apparatus in which the precipitate is formed by the introduction of steam through perforated coils 23 and 24 which are disposed concentrically in the lower portion of the precipitation zone in connection with supply pipes 23^a and 24^a extending through openings in the cover.

The material is fed into the mixing zone of the funnel immediately above the propeller, through a plurality of pipes 25 likewise extending through openings of the

cover for connection with a supply manifold 26 and the flow through each pipe is controlled by a manually adjustable angle valve 27.

- 5 In the operation of the apparatus, the propeller produces a circulating current of a liquid with which the tank is filled to a level determined by an overflow-opening 28 in the circumferential wall of the tank, the current 10 passing upwardly through the precipitation zone and downwardly through the funnel and around the ends thereof, and in order to prevent the liquid in the current swirling horizontally, both the interior of the 15 funnel and the precipitation zone exteriorly of the same, are divided by radial partitions 29 and 30. A drain opening 31 in the bottom of the tank provides for the discharge of liquid and settled matter when the apparatus 20 is not in operation.

In the performance of the process of precipitating the sucrose and lime constituents of the cold waste water, the tank is filled with barren mother liquor to the level determined by the point of overflow. This is 25 preferably accomplished by first filling the tank with pregnant cold waste and then forming the "hot saccharate precipitate" of the sucrose and lime contained therein by a 30 circulatory movement of the liquor induced by the movement of the propeller, and by the introduction of a heating fluid through the perforated coils to a temperature of from 80° to 85° C.

35 After the precipitate has been formed and the mother liquor is substantially barren of precipitable matter, fresh cold waste is delivered into the mixing zone through the pipes 25. The feed is immediately inter- 40 mixed with the current of barren liquor passing downwardly through the funnel and thereby diluted to many times its volume and while it passes upwardly through the precipitation zone, its sucrose and lime whose 45 concentrations were reduced in proportion to the dilution, are precipitated by the heat constantly supplied by the steam entering from the perforated coils 23 and 24.

It will be evident that in order to obtain 50 the most satisfactory results, no precipitate should be formed before the feed is diluted and since the current of barren liquor passing through the funnel is of comparatively high temperature, it is obviously essential 55 that the dilution of the cold waste take place immediately upon its entering the tank.

It is for this reason advisable that the feed 60 pipes have their outlets in as close proximity to the propeller as is permissible for the intermixture of the inflowing waste water with the circulating current of barren liquid.

In order to produce the required dilution 65 of the waste water, the propeller is operated to produce a current velocity many times that of the feed-stream, it having been found

that approximately 40 cubic feet of current against 2 cubic feet of feed per unit of time have produced a desirable reduction in the concentration of precipitable substances (from 1% by weight in the cold waste to 70 .05% in the mixture).

It is essential that the velocity of the current in the precipitation zone be regulated in ratio to its volume to allow for precipitation to proceed practically to completion 75 before the current reaches the level determined by the overflow, so that the liquor entering the funnel at the upper end thereof be substantially barren of precipitable matter for dilution of the inflowing cold waste, an object readily accomplished by varying the speed of the propeller or the dimensions of the tank.

It may further be advisable to increase or decrease the streams of inflowing cold waste 85 according to the current velocity, temperature and other variable conditions in the tank and it will be understood that this is easily done by equipping the apparatus with the maximum number of pipes and then regulating their operation by means of the 90 valves 27.

Having thus described our invention, what we claim and desire to secure by Letters Patent is:

1. Apparatus for the precipitation of precipitable substances from their solutions comprising in combination, a vessel adapted to contain a diluent bath and having an overflow to maintain a determinate volume of said bath by the discharge of surplus liquid, the vessel being divided into a mixing zone and a precipitation zone communicating in the lower portion of the same, means in the mixing zone adapted to produce a current circulating from the mixing zone downwardly into the precipitation zone, means to feed solution into the bath in the mixing zone, and means to subject the bath in the lower portion of the precipitation zone to a precipitating heat.

2. Apparatus for the precipitation of precipitable substances from their solutions, comprising in combination, a vessel adapted to contain a diluent bath and having an overflow to maintain a determinate volume of said bath by the discharge of surplus liquid, the vessel being divided into a mixing zone and a precipitation zone communicating in the lower portion of the same, a propeller in the mixing zone adapted to produce a current circulating from the mixing zone downwardly into the precipitation zone, means to feed solution into the bath in the mixing zone, in close proximity to the propeller, and means to subject the bath in the lower portion of the precipitation zone to a precipitating heat.

3. Apparatus for the precipitation of precipitable substances from their solutions

comprising in combination, a vessel adapted to contain a diluent bath and having an overflow to maintain a determinate volume of said bath by the discharge of surplus liquid, the vessel being divided into a mixing zone and a precipitation zone communicating in the lower portion of the same, means in the mixing zone adapted to produce a current circulating from the mixing zone downwardly into the precipitation zone, distributive means to feed solution into the bath in the mixing zone, and means to subject the bath in the lower portion of the precipitation zone to a precipitating heat.

15 4. Apparatus for the precipitation of precipitable substances from their solutions comprising in combination, a vessel adapted to contain a diluent bath and having an overflow to maintain a determinate volume 20 of said bath by the discharge of surplus liquid, the vessel being divided into a mixing zone and a precipitation zone communicating in the lower portion of the same, means in the mixing zone adapted to produce a current circulating from the mixing zone downwardly into the precipitation zone, means to feed solution into the bath in the mixing zone, means to oppose lateral deflection of the current in the bath, and 25 means to subject the bath in the lower portion of the precipitation zone to a precipitating heat.

30 5. Apparatus for the precipitation of precipitable substances from their solutions comprising in combination, a vessel adapted to contain a diluent bath and having an overflow to maintain a determinate volume 35 of said bath by the discharge of surplus liquid, the vessel being divided into a mixing zone and a precipitation zone communicating in the lower portion of the same, a propeller in the mixing zone adapted to produce a current circulating from the mixing zone downwardly into the precipitation zone, a plurality of conduits connected to 40 distribute a solution in the bath in the mixing zone immediately above the propeller, and means to subject the bath in the lower

portion of the precipitation zone to a precipitating heat.

50 6. Apparatus for the precipitation of precipitable substances from their solutions comprising in combination, a vessel adapted to contain a diluent bath and having an overflow to maintain a determinate volume 55 of said bath by the discharge of surplus liquid, the vessel being divided into a mixing zone and a precipitation zone communicating in the lower portion of the same, radial partitions in the zones to oppose lateral deflection of the current, means in the mixing zone adapted to produce a current circulating from the mixing zone downwardly into the precipitation zone, means 60 to feed solution into the bath in the mixing zone, and means to subject the bath in the lower portion of the precipitation zone to a precipitating heat.

65 7. Apparatus for the precipitation of precipitable substances from their solutions, 70 comprising in combination a vessel, means to produce a current of liquid in the vessel in a circulatory movement, a feed adapted to enter material into the current of liquid, and means for heating the current.

75 8. Apparatus for the precipitation of precipitable substances from their solutions, comprising in combination a vessel, means to produce a current of liquid in the vessel 80 in a circulatory movement, a feed adapted to enter material into the current of liquid, at a plurality of points, and means for heating the current.

85 9. Apparatus for the precipitation of precipitable substances from their solutions, comprising in combination a vessel, means to produce a current of liquid in the vessel, past a determinate point of feed, a feed adapted to enter material into the current at said point, and means for heating the 90 current.

In testimony whereof we have affixed our signatures.
